UNITED STATES PATENT OFFICE.

HARRY AGLOW, OF NEW YORK, N. Y., ASSIGNOR TO ARTCRAFT METAL STAMPING CORPORATION, A CORPORATION OF NEW YORK.

LIGHTING FIXTURE.

Application filed April 23, 1925. Serial No. 25,196.

The present invention relates to lighting fixtures and methods of making the same and is more particularly directed toward stamped sheet metal fixtures so made that they do not appear to be stampings.

Many forms of lighting fixtures are made from brass, aluminum or white metal in the form of one or more castings. Chandelier and ceiling fixtures when made of these castings are frequently provided with gracefully shaped holes or apertures which provide ornamentation, break up the surface into more or less distinct parts, and facilitate the carrying out of the ornamental scheme of the fixture. They also reduce the weight of the fixture and sometimes permit making it out of a number of identical cast parts suitably assembled.

Stamped fixtures as heretofore made have generally had a stamped pan with surface ornamentation only. In addition to the surface ornamentation these pans were provided in some cases with a cut out center to accommodate a glass bowl. The common types of fixtures with these stamped bodies have compared rather unfavorably with the more elaborate cast fixtures, because the same or equal artistic merit was difficult or impossible to attain by stamping. The available designs, both as to shape and surface ornamentation, suitable for this type of fixture have been used by so many manufacturers that they have become commonplace and it is more difficult to produce a new and distinctive design. For these, and other reasons, the tendency in the manufacture of high class fixtures has been more toward the cast fixture, notwithstanding the greater expense for materials, shipping and handling charges, and the increased labor charges for making castings over the cost of a stamping operation.

The present invention contemplates the provision of a stamped sheet metal lighting fixture which may be provided with holes or apertures which are drawn in such a manner as to give the stamping the appearance of a casting. The invention also contemplates the provision of a stamped fixture with what appears to be thick massive arms and an encircling ring such as are common in fixtures.

Furthermore the invention contemplates the manufacture of a stamped fixture body which may be provided with surface orna-

mentation of the same type which would appear on cast parts whereby the cast parts, such as arms may be attached to the stamped body without any appreciable line of demarcation.

The accompanying drawings show, for purposes of illustration, two of the many possible forms of lighting fixture bodies in which the present invention may be embodied, together with views showing a typical arrangement of steps in carrying out the manufacture of the fixture body, it being understood that the drawings are merely illustrative.

In these drawings:

Fig. 1 is an edge view of the sheet metal blank, suitable for making a lighting fixture body;

Fig. 2 is a fragmentary sectional view; and Figure 3 is a fragmentary top plan view, these are two figures showing an initial step in forming a plate into a lighting fixture body.

Fig. 4 is a fragmentary sectional view, and Figure 5 is a fragmentary plan view inverted, these two figures showing a subsequent step in the formation of a lighting fixture body, rudimentary recess having now been formed;

Figure 6 and 7 are views similar to Figures 4 and 5 respectively, showing the blank after a still later step in the stamping operations;

Figures 8 and 9 are views similar to Figures 6 and 7 respectively, showing the blank after a still later step;

Figure 10 is a fragmentary sectional view through a finished lighting fixture body and showing one of the apertures;

Figure 11 is a sectional view taken through one of the holes in the fixture and looking toward the periphery of the stamping;

Figure 12 is a sectional view showing the arm formed between two of the apertures;

Figure 13 is an elevational view of a five light ceiling fixture using the present stamped body, a portion of the fixture being shown in dotted lines.

In making lighting fixture bodies, according to the present invention, one uses a sheet metal blank 10 of appropriate gage and shape, and subjects it to a number of stamping operations, so related that the material is gradually pressed or drawn into the desired shape without thinning the material or

weakening it. During the later steps of the process the dies are such as to give the stamping its surface ornamentation. The drawings show a typical arrangement or layout of steps in the stamping up of one form of lighting fixture body. The actual number of steps in any particular case will, of course depend upon the conditions which arise therein. A central portion of the blank 10 is pressed downwardly as indicated in Figures 2 and 3 to form more or less plate-shaped body 11. This initial step, is merely a preliminary step and may sometimes be omitted in making certain forms of lighting fixture bodies. I prefer, however, to employ this initial step as it makes it unnecessary to draw the material excessively in a later step. Figures 4 and 5 show the blank after it has been subjected to one or more additional stamping operations. Here it will be noted that the body now assumes a more ornamental shape than it did in the form shown in Figures 2 and 3. The surface of the stamping is more gracefully curved and the formation of regularly spaced recesses 12 and 13 are already started, which at this stage are merely rudimentary. The metal is not drawn into any sharp corners or at sharp angles. The periphery of the stamping is drawn upwardly as indicated at 14 to initiate the formation of a deep rim.

Figures 6 and 7 show a later step in the process of forming the body to shape. As here shown, the depressed or recessed areas 12' and 13' are deeper and the angles into which the stamping is drawn are more sharply defined. The rim 14' is drawn deeper and trimmed if necessary. The dies for this step may be such as to initiate the formation of surface contour or ornamentation. For example one may form ridges, valleys or other shapes which will later become a foundation for the more intricate surface ornamentation of the finished body. A few of the curves which might thus be formed is indicated in these figures at 15, 16, 17 and 18.

In Figures 8 and 9 the stamping is shown as it appears after one or more additional pressing operations have been performed on it. It will be noted that the curves and angles are sharper than they were in the preceding stages in making the body, and that the outer edge of the stamping is now drawn upwardly as indicated in 14" to provide a comparatively deep side wall. The recesses 12" and 13" are well defined and their entire side walls are of substantial depth.

Figures 10, 11 and 12 indicate a lighting fixture body on which the stamping operations have been completed. These figures showing that surface ornamentation has been impressed into a metal with consider-

able detail, it being understood that no effort has been made to show in these drawings the minute details of surface ornamentation actually used in a commercial fixture. A more detailed showing of such a lighting fixture part is to be found in Design Patent 66,059 of December 9, 1924, granted on an application filed by me June 27, 1924.

During the last steps in the process, the bottoms of the recesses or depressions are punched out to provide apertures 20, and the sidewalls of these depressions are forced into a position, such that the edges of the punched holes are invisible from underneath. This may conveniently be done by forming the punch to stretch the marginal portion 21 slightly. The material between the holes becomes channel-shaped as indicated in Figure 12.

During the finishing operations, the upper edge of the rim of the stamping is preferably turned in as indicated at 22 in Figures 10 and 11. This seems to provide a more rigid stamping, as well as providing an outside rim of even smooth appearance and having substantial depth to make the stamping have the appearance of a casting.

The stamping may be made up to have two, three, four, five or more holes or apertures to provide the desired number of arms according to the style and size of fixture intended. They may have any desired surface ornamentation, which may be applied to a stamping, or drawn into various shapes as desired.

Figure 13 shows in full lines a part of the body and part of the arms of a five light ceiling fixture. Here the body 30 is provided with a number of holes or apertures 31, three of which appear in this figure of the drawings, the other two being hidden. Between each of these apertures 31 will be found the channel shaped arms 32 above referred to, which appear as cast arms. The upper peripheral portion 33 of the fixture body may be a plain cylindrical surface which appears like the outside of a casting. Surface ornamentation may be impressed as desired, a suitable form being indicated.

In making up the fixture it is preferable to use a number of cast arms, such as the arms 34, which may be fastened to the lighting fixture body in the usual manner, such as by the use of screws threaded into the arms through the back side of the lighting fixture body. These arms are clamped against the lighting fixture body between the apertures 31, and adjacent the periphery of the fixture. They are preferably provided with surface ornamentation of the type suitable for cast lighting fixture arms and are preferably given such shape and style of ornamentation that they fit the stamped

body very closely and the ornamentation on the arms merges into the ornamentation on the body.

For example, the arm shown in Design

5 Patent 66,174, granted Dec. 9, 1924, may be used with a body such as shown in Design-
Patent 66,059, above referred to, to produce
a fixture such as shown in Design Patent
66,173, granted Dec. 9, 1924. In this way an
10 illusion of the cast fixture body with integral
arms, is carried out.

In this figure the lower part of the spindle
for the fixture is shown at 35 in full lines
while the other parts of the fixture is shown
15 in dotted lines. A canopy is shown at 36
on the outer portion of the arms as indi-
cated at 34', the sockets at 37, the bobeches
38, the lamps at 39, and the tassel at 40.

It is obvious that the invention may be
20 embodied in many forms and constructions,
and I wish it to be understood the particu-
lar forms shown are but a few of the many
forms. Various modifications and changes
being possible, I do not limit myself in any
25 way with respect thereto.

What is claimed is:

1. A lighting fixture body in the form of
a sheet metal stamping convex from under-
30 neath and provided with apertures whose
side walls are drawn upwardly to give the
body the appearance of substantial thick-
ness when viewed from underneath.

2. A lighting fixture body in the form of
a sheet metal stamping having a substan-
35 tially flat outer portion, a central portion be-
low the outer portion, the intermediate por-
tion being provided with apertures whose
side walls are drawn upwardly to give the
body the appearance of substantial thickness
40 when viewed from underneath.

3. A lighting fixture body in the form of
a sheet metal stamping having apertures
whose side walls are drawn upwardly to
give the body the appearance of substantial
45 thickness when viewed from underneath, the
side walls of adjacent apertures forming an
arm of channel shaped cross section to simu-
late the appearance of a cast arm.

4. A lighting fixture body in the form of
50 a sheet metal stamping having apertures
whose side walls are drawn upwardly to
give the body the appearance of substantial

thickness when viewed from underneath, the
periphery of the stamping being drawn up-
wardly so that the edge of the body appears
55 thick.

5. A lighting fixture body in the form of
a sheet metal stamping having a substan-
tially flat outer portion, a central portion below
the outer portion, the intermediate portion
60 being provided with apertures whose side
walls are drawn upwardly to give the body
the appearance of substantial thickness
when viewed from underneath, the periph-
ery of the stamping being drawn upwardly
65 so that the edge of the body appears thick.

6. A lighting fixture body in the form of
a sheet metal stamping having apertures
whose side walls are drawn upwardly to
give the body the appearance of substan-
70 tial thickness when viewed from under-
neath, the side walls of adjacent apertures
forming an arm of channel shaped cross sec-
tion to simulate the appearance of a cast
75 arm, the periphery of the stamping being
drawn upwardly so that the edge of the
body appears thick.

7. A lighting fixture body in the form of
a sheet metal stamping having apertures
whose side walls are drawn upwardly to give
80 the body the appearance of substantial
thickness when viewed from underneath, the
upper edge of said side walls being so
shaped that the thickness of the material
thereof is invisible from underneath.

8. A lighting fixture body in the form of
a sheet metal stamping having arms of chan-
nel shaped cross section to simulate the ap-
pearance of cast arms, the upper edge of
85 said side walls being so shaped that the
thickness of the material thereof is invisible
from underneath.

9. A lighting fixture body in the form of
a sheet metal stamping having apertures
whose side walls are drawn upwardly to give
95 the body the appearance of substantial thick-
ness when viewed from underneath, the side
walls of adjacent apertures forming an arm
of channel shaped cross section to simulate
100 the appearance of a cast arm, the upper edge
of said side walls being so shaped that the
thickness of the material thereof is invisible
from underneath.

HARRY AGLOW.
